2 SHEETS - SHEET 2.

UNITED STATES PATENT OFFICE.

FURNEY F. GREEN, OF COALGATE, OKLAHOMA.

METALLIC RAILROAD-TIE.

1,110,198.

Specification of Letters Patent. Patented Sept. 8, 1914.

Application filed November 25, 1913. Serial No. 803,017.

To all whom it may concern:

Be it known that I, FURNEY F. GREEN, a citizen of the United States, residing at Coalgate, in the county of Coal and State 5 of Oklahoma, have invented a new and useful Metallic Railroad-Tie, of which the following is a specification.

This invention relates to metallic railroad ties and is more particularly designed as 10 an improvement upon the structure disclosed in Patents #1,050,271, dated January 14, 1913, and #1,069,779, dated August 12, 1913.

One of the objects of the invention is to 15 provide an all metal tie having a novel form of detachable rail brace which can be easily placed in or removed from position and which will operate efficiently to prevent the rails from tilting laterally.

20 A further object is to provide improved spacing means whereby rails of different sizes may be fixedly secured upon ties of a standard size.

Another object is to provide improved 25 anchoring means upon the bottom of the tie whereby creeping is prevented.

A further object is to provide a tie of this character which can be constructed for use at switches.

30 With the foregoing and other objects in view which will appear as the description proceeds, the invention resides in the combination and arrangement of parts and in the details of construction hereinafter described and claimed, it being understood that changes in the precise embodiment of the invention herein disclosed, can be made within the scope of what is claimed, without departing from the spirit of the invention.

35 In the accompanying drawings the preferred form of the invention has been shown.

In said drawings:—Figure 1 is a plan view of a tie having the present improvements combined therewith, the positions of 40 rails on the tie being indicated by dotted lines. Fig. 2 is a vertical longitudinal section through the structure shown in Fig. 1. Fig. 3 is a bottom plan view of one end portion of the tie. Fig. 4 is a perspective view of one of the braces. Fig. 5 is a section through a portion of the tie and showing the seat provided for one of the braces. Fig. 6 is a perspective view of a spacing 45 clip. Fig. 7 is a plan view of a modified form of tie especially designed for use at a point remote from the tongue of a switch.

Fig. 8 is a plan view of another modified form of tie particularly designed for use under the tongues of a switch. Fig. 9 is a section on line A—B Fig. 8. Fig. 10 is a section on line C—D Fig. 7. Fig. 11 is a perspective view of the wear plate shown in Fig. 9, the same being inverted. Fig. 12 is a section through a rail and showing insulating plates adapted to be used in connection therewith. Fig. 13 is a view similar to Fig. 12 and showing a slightly modified arrangement of insulating plates. Figs. 14 and 15 are detail views of the insulating plates. Fig. 16 is a section through a portion of the tie and showing a spacing strip and insulating plates applied to a rail.

Referring to the figures by characters of reference 1 designates a trough-like tie body formed of metal and having parallel longitudinally extending ribs 2 connected at desired intervals by cross ribs 3 which can also be integral with the side walls of the body 1. The ends of the body are closed and bottom plates 4 are formed under the end 50 portions of the body and have downwardly extending longitudinal and transverse ribs 5 adapted to engage the road bed and thus constitute an anchoring means to prevent the tie from creeping. Flanges 6 extend laterally from the bottom plates 4 and also 55 extend from the ends of the body and are adapted to receive rivets or other fastening means such as indicated at 7 for holding the bottom plates 4 in position. Notches 8 60 may be provided in these flanges to receive spikes or the like employed for securing the tie to a bridge structure.

These portions of the tie adapted to support the rails R are provided with transverse 65 ribs 9 arranged close together as shown in Fig. 2, one of these ribs 9 co-operating with a thickened rib 3' to form a transverse pocket 10 which is intersected by the longitudinal ribs 2. The transverse ribs 9 of 70 each group are interposed between the thickened transverse ribs 3' and another transverse rib 3 and the ribs 3 and 3' extend up to the top of the tie while the ribs 9 have their upper edges below the top of the tie. 75 These upper edges as well as the upper edges of the longitudinal ribs 2 are adapted to project into grooves 11 formed in the bottom of a wear plate 12 which fits snugly against one transverse rib 3 but is spaced 80 slightly from the rib 3', that edge of the plate 12 nearest the rib 3' being provided

- with an upstanding shoulder 12' constituting an abutment for the outer base flange of the rail R. The inner base flanges of the rails are adapted to be engaged by jaws 13 which, in turn, are engaged by the threaded ends 14 of spreading and holding strips 15, these strips being pivotally connected as at 16, and being adapted to be held substantially in alignment by a bolt 17.
- 10 Hooked members 18 extend downwardly from the jaws 13 and are adapted to engage the adjacent cross ribs 3, as shown in Fig. 2.
- In order that the rails R may be properly braced so as to be held against tilting when subjected to lateral pressure, a plate 18' is fitted against the under side of the outer portion of the head of each rail, this plate being inclined and having flat fingers 19 depending therefrom and adapted to project into the pockets 10. The ribs 2 extend into the slots 20 formed between the fingers and the upper end walls of the slots are adapted to fit within notches 21 formed in the upper edges of the ribs 2 between the ribs 3' and the adjacent ribs 9. It is to be understood of course that the bracing plates 18 are to be placed in position before the rails are positioned so that, by subsequently placing the rails on the wear plates 12 their heads, by lapping and bearing downwardly on the plates 18, will hold said plates against accidental removal from the tie, as will be obvious by referring to Fig. 2.
- 35 It is to be understood that should the rails be smaller than standard rails, smaller brace plates 18 can be used and, furthermore, spacing strips can be interposed between the sides of the base flanges of the 40 rails and the clamping strips or jaws 13 and shoulders 12'. One of these spacing strips has been shown at 22 in Fig. 6. Said strip has depending terminals 23 adapted to engage the sides of the tie body so as thus to 45 hold the spacing strip against longitudinal displacement. Upward displacement of the strip is prevented by the jaws 13 and the brace plates 18 respectively.
- Should it be desired to insulate the rails 50 from the tie, insulating plates such as shown in Figs. 12 to 15 inclusive can be used. One of these plates can be substantially U-shaped in cross section, as shown in Fig. 15, so as to straddle one of the base flanges of the 55 rail while the other insulating plate can be formed with a U-shaped base portion 25 adapted to embrace one of the base flanges of the rail, there being a web 26 extending upwardly from the base portion 25. This 60 web is adapted to engage one side of the web of a rail and has an outstanding upper flange 27 designed to engage the head of the rail. Thus the rail will be insulated from the brace plates 18.
- 65 It is to be understood of course that instead of utilizing the means shown in Figs. 1 and 2 for securing the jaws 13 in place, said jaws can be formed with depending flanges 28 designed to be engaged by a bolt 29 extending transversely through the ribs 3, 3' and 9, it being understood of course that the brace plates 18' shown in Fig. 10, will be similar to the brace plates shown in Figs. 2 and 4 with the exception that an opening 30 will be provided therein for the reception 75 of the bolt 29.
- In order that the ribs 2 and 3 as well as the ribs 9 may be properly reinforced transversely, a horizontal partition 31 is extended throughout the length and width of the tie, as shown in Fig. 2, this horizontal partition being cut away between the ribs 3' and 9 so that the pockets 10 will not be obstructed.
- It is to be understood that the construction of the tie can be modified to support various arrangements of rails. For example, and as shown in Fig. 7, the tie can be made of such length as to extend under four rails diverging from a switch, the wear plates 31 corresponding with the plates 12, being disposed obliquely where necessary and the arrangement of ribs under these plates being similarly changed so that the wear plates will be properly supported. 85 Also—as shown in Fig. 8, the tie can be so constructed as to extend under the points of the switch, the top plates 32 being of such width as to allow the movable members of the switch to slide back and forth thereon, 90 these members being indicated at 33. In this construction it will of course be necessary to have upstanding rail engaging tongues 34 on the plates 33 for holding the inner base flanges of the rails R. These 95 tongues can be cast integral with the plates 32 or can be detachably connected thereto in any preferred manner. Any other desired changes necessary in order to adapt the ties for use at different points, can be made. 105
- What is claimed is:—
1. A metallic railway tie including a body having longitudinal and transverse ribs, certain of said transverse ribs coöperating to form a pocket, the longitudinal ribs intersecting the pocket, means for supporting a rail at one side of the pocket, a brace plate for engaging one side of the supported rail, and spaced fingers depending from the plate and insertible into the pocket at the 110 sides of the longitudinal ribs.
  2. A metallic railway tie including a body having longitudinal and transverse ribs, certain of said transverse ribs coöperating to form a pocket, the longitudinal ribs intersecting the pocket, means for supporting a rail at one side of the pocket, a brace plate for engaging one side of the supported rail, and spaced fingers depending from the plate and insertible into the pocket at the sides of 115 120 125 130

the longitudinal ribs, said longitudinal ribs having notched upper ends for the reception of the brace plate.

3. A metallic railway tie including a body 5 having a group of transverse rail supporting ribs, longitudinal ribs in the body, certain of said transverse ribs coöperating to form a pocket intersected by the longitudinal ribs, the upper edges of the longitudinal 10 ribs being notched within the pocket, a wear plate fitted upon and receiving the upper edges of the group of transverse ribs, a brace plate for engaging one side of a rail, said plate having spaced fingers projecting 15 into the pocket and at the sides of the longitudinal ribs, the upper end walls of the slots formed between the fingers being seated in the notches.

4. A metallic railway tie including a body 20 having a group of transverse rail supporting ribs, longitudinal ribs in the body, certain of said transverse ribs coöperating to form a pocket intersected by the longitudinal ribs, the upper edges of the longitudinal 25 ribs being notched within the pocket, a wear plate fitted upon and receiving the upper edges of the group of transverse ribs, a brace plate for engaging one side of a rail, said plate having spaced fingers projecting into 30 the pocket and at the sides of the longitudinal ribs, the upper end walls of the slots formed between the fingers being seated in the notches, an insulating plate for engagement by the brace plate and including a 35 web, an upper flange, and a U-shaped base, another insulating plate U-shaped in cross section, the two insulating plates being mounted on the wear plate, and a rail having its base flanges projecting into the 40 U-shaped plates and fitting snugly against the web and top flange.

5. A railway tie including a body having a transverse pocket, longitudinal ribs intersecting the pocket and having notched upper 45 edges within the pocket, a wear plate, a spac-

ing strip upon the wear plate and having depending terminals for lapping the sides of the tie, a brace plate at one side of the wear plate for engaging one side of a rail, fingers depending from the plate and into 50 the pocket at the sides of the longitudinal ribs, the upper end walls of the slots between the fingers being adapted to be seated in the notches, and additional rail securing means mounted on the tie, the wear plate being disposed between the brace and said securing means.

6. A railway tie including a body portion having a transverse pocket, longitudinal ribs intersecting the pocket and having notched 60 upper edges within the pocket, a wear plate, a spacing strip upon the wear plate and having depending terminals for lapping the sides of the tie, a brace plate at one side of the wear plate for engaging one side of a 65 rail, fingers depending from the plate and into the pocket at the sides of the longitudinal ribs, the upper end walls of the slots between the fingers being adapted to be seated in the notches, additional rail securing means mounted on the tie, the wear plate being disposed between the brace and said securing means, a rail supported by the wear plate and at one side of the spacing 70 strip, a U-shaped insulating plate engaged by one base flange of the rail, an insulating plate having a U-shaped portion engaging the other base flange of the rail, said last named insulating plate including a web and a top flange, the brace plate being adapted 75 to engage the flange and to be insulated thereby from the rail.

In testimony that I claim the foregoing as my own, I have hereto affixed my signature in the presence of two witnesses.
